UNITED STATES PATENT OFFICE.

JOHN F. PARKER, OF PORTLAND, MAINE.

TELEPHONE.

Application filed May 4, 1928. Serial No. 275,145.

My invention relates, in general terms, to telephones, but specifically, deals with certain novel features, both operative and structural, which I have incorporated in the ordinary semi-portable desk or extension set.

One of the objects I have in view is to provide a telephone in which the receiver is a fixed element on the instrument,—the set being operable with one hand and raised bodily to the operator's head when in use.

Another object is the provision made whereby the electric circuit through the telephone may be closed at any time subsequent to its being lifted from its resting place on a desk or table by simply pressing a button operable by the hand which holds the instrument, this act effecting the release of a plate carrying a plunger operable in a jack. The plunger is normally locked and held in a position to provide an open or inoperative telephone circuit, but upon being released, brings the proper connections together in the jack to close the circuit.

Another object concerns the arrangement whereby the transmitter may be gagged, or made inoperative, temporarily, so that the user of the instrument may converse with a party in his presence without the one with whom his telephone is in connection being aware that this conversation with the third party is taking place.

A further object resides in the feature which permits the circuit to remain closed in case, for instance, the one answering a call is required to leave the telephone to summons another person wanted at the telephone.

And a still further object is the provision made whereby the circuit is automatically opened when the instrument is again laid on its base on the desk—to remain open until the telephone is again lifted and the circuit manually closed by the actuation of the hereinbefore mentioned push button.

Other objects and advantages will be apparent from the description hereinafter found in the specification, and for the purpose of illustrating my invention I have prepared the accompanying drawings in which is disclosed one embodiment which, at the present time, I consider preferable to other possible forms in which the invention might be carried out.

In the drawings,—

Fig. 1 is an elevation, partly in section,

of my telephone, the parts as arranged showing the instrument in "open" circuit,—the base plate being in retracted position;

Fig. 2 is a sectional plan taken on line 2—2, Fig. 1, showing the shutter employed to gag the transmitter;

Fig. 3 is an inverted plan of the base portion of the telephone, showing the jack and a portion of the wiring arrangement;

Fig. 4 is a plan view of the leg on which the telephone rests when laid on its side;

Fig. 5 is a fragmentary elevation, partly in section, illustrating the mechanical parts, only, of the telephone as they appear when the instrument is in "closed" circuit,—the base plate being in extended position;

Fig. 6 is an enlarged sectional elevation taken on line 6—6, Fig. 1, showing the plunger and jack which opens and closes the circuit through the telephone,—this figure showing the circuit "open";

Fig. 7 is the same as Fig. 6 except that the circuit is "closed" and Fig. 8 is the wiring diagram.

Similar reference characters identify like parts in all views.

Referring to the drawings, 1 represents the base, 2 the tubular handle, 3 the receiver and 4 the transmitter of my improved telephone. The two last named elements, 3 and 4, may be of any approved type or style and in so far as the novelty of my invention is concerned do not, of themselves, form a part thereof, except in combination with the other elements.

Rising from the base and extending upwardly into the tubular handle 2 is a hub 5 centrally bored to receive the guide bushing 6, reciprocable in which is a stud 7. The lower end of this stud is secured in the axially movable base-plate 8 by means of the screw 9.

I preferably cover the base-plate with a felt protecting pad 10, employing a ring member 11 with which to draw the pad tightly across the bottom of the base-plate.

A spring 12 provides a yielding thrust on the top of the base-plate tending to force it out of its position within the lower portion of the base 1.

On the top end of the stud 7 is a head 13 and a latch lever 14 engages this head, when the base-plate is in its retracted or extreme inward position within the base, locking the parts together and causing the circuit

through the telephone to be opened,—the spring 12 now being under maximum compression.

The latch lever is pivotally secured to the handle 2 through the agency of the bracket 15 and on its upper end a push button 16 extends outwardly through the wall of the handle. A spring 17 operates to yieldingly hold the hook end of the latch lever inwardly, or toward the head 13.

With the telephone lifted free of the table or desk, a pressure applied to the push button 16 releases the head 13 from the latch lever hook and allows the base-plate to move outwardly, or into its extended position within the base 1, as illustrated in Fig. 5, in which position the telephone circuit is "closed".

The reciprocations of the base-plate 8 within the base 1 provide the necessary movements in a plunger and jack mechanism for opening and closing the telephone circuit.

Referring to Figs. 1, 6 and 7 the method of operating this jack will be clearly understood. Secured to the base-plate 8 is a plunger 18 which extends upwardly into the hole 19 made in a depending boss 20 within the base 1. Secured to the face of this boss is an insulating block 21 to which are fastened three jack springs 22,—these composing the elements in the jack. In the Figs. 6 and 7 I have shown but one of these springs. The proper wiring connections are made with these springs, about which more will be said hereinafter in the specification. It might be well to state at this time, however, that in some systems of wiring the telephone but one of the jack springs would be required, in others perhaps four,—the principle involved being the same in all cases.

The plunger is a composite structure, there being an upper portion having a reduced end 18' which is secured in the lower portion, and between the shoulders thus made is a sleeve 23 and a collar 24 made of any hard insulating material. Surrounding a turned down portion of the sleeve is a ferrule 25 made of any suitable conductive material. This ferrule is completely insulated from the metallic plunger 18 and reduced portion 18'.

When the base-plate is in retracted position within the base, as seen in Figs. 1 and 6, the jack springs ride on the insulating sleeve 23, and when the base plate is extended, as shown in Figs. 5 and 7, these springs all bear on the conductive ferrule 25.

Referring to Figs. 1, 2 and 5, wherein are shown the parts employed to temporarily gag or cut out the transmitter, 26^a and 26^b represent the two parts of which I preferably make the transmitter tubular adapter. The lower part screws into the transmitter

casing and is provided with a perforated partition 27 in which are holes 28. The upper portion of the adapter, into which is screwed the mouth-piece 29, is secured to the lower portion by the screws 30.

Operating through a slot in the section 26^b is a perforate shutter or disc 31 having holes 32 which match the holes 28 in the partition 27. Integral with or secured to the shutter is an arm 33 which extends through an opening 34 into the interior of the handle 2, terminating in an upturned portion 33'. A flat spring 35 is secured to the handle 2 and acts normally to place a yielding strain on the portion 33', tending to force the shutter arm further into the telephone handle 2.

Secured to the stud 7 is a plate 36 having an outer bevelled end which at certain times engages the upturned end 33' of the arm 33.

The two elements, 35 and 36, in co-action, control the automatic movement of the shutter 31. For instance, when the telephone rests on the plate 8, the stud 7 is in its uppermost position, the circuit of the telephone being at this time open, and the plate 36 forces the arm 33 outwardly (see Fig. 1), bringing the holes 28 and 32 into disalignment.

In this position of the shutter the transmitter is gagged,—by which I mean that the passage from the mouth-piece to the diaphragm of the transmitter is closed, preventing the vibration of the air caused by the articulations of the vocal organs of the speaker being transmitted to the diaphragm. The particular function exercised by the shutter at this time—or when the telephone is at rest on its base—is not, however, to prevent transmission of sound, but to close the passage-way to the admission of dust, dirt or foreign matter which by collecting on the diaphragm causes it to act less effectively.

Upon lifting the instrument from the desk and releasing the stud 7 from engagement with the lever 14 by the actuation of the push button 16, the plate 36 drops, allowing the spring 35 to force the arm 33 inwardly and the two sets of holes, 28 and 32, to align—thus making air communication with the diaphragm 37 from the outside, through the mouth-piece, possible. The positions of the parts now under consideration are clearly shown in Fig. 5, in which view the instrument may be considered as being removed from the desk and held by the speaker's hand in the act of telephoning.

It is obvious, if further reference be had to Figs. 5 and 7, that the telephone, after being raised from the desk, has also been placed in closed circuit with the service lines through the manipulation of the push button 16 and that while the instrument is thus held, the transmitter may be manually

gagged by again pressing the button 16 and holding it in its retracted position,—the hooked end of the latch lever 14 abutting on the portion 33', forcing the arm 33 outwardly against the resistance of the spring 35 and resulting in bringing the holes 28 and 32 into disalignment, as shown in Fig. 1.

The manual actuation of the shutter 31 can be accomplished only after the telephone 10 has been lifted from the table and placed in closed circuit; but, as a matter of fact, this is the only time at which this method of operating it is called for.

In some cases it is desirable to lay the 15 telephone on its side, and to do this and prevent its rolling I supply the forked leg 38 shown in plan in Fig. 4.

Any convenient means may be employed 20 by which to secure together the base, the handle, the forked leg and the receiver,—as for instance, by the long bolts 39.

The wiring diagram is shown in Fig. 8. Starting with the receiver R, one wire passes 25 out of the base 1, the other wire, b, makes connection with one of the jack springs 22. From the transmitter T, the wire d, connects with another jack spring, and the other wire, c, proceeds out of the base as does also the wire e which originates from the third 30 and last jack spring. The three wires, a, c, and e which extend together out of the base continue to the coils, condenser, bells etc. and are connected up, as is, in fact, all the wiring, except that the jack is included in the 35 circuit in the usual or conventional manner of telephone equipment.

The operating features of my telephone differ in many respects from the ordinary 40 type of instrument. The user first lifts the telephone from its resting place, brings the receiver to his ear and inclines the handle so that the transmitter comes within convenient range of his mouth. The act of lifting the instrument, however, does not 45 make it possible, as yet, to call the central exchange,—this being accomplished by lightly pressing the button 16 which releases the plunger 7 and allows the spring 12 to force the base-plate 8 into extended position.

50 The movement of the base-plate outwardly of the base 1 changes the relative positions of the jack springs 22 from their former location on the insulating sleeve 23 to common contact with the conductive ferrule 25. This closes the electrical circuit through the 55 telephone, and it is now possible to reach the central office and put in the call for the party with whom it is desired to converse.

After the party calling has completed his 60 conversation, the telephone is returned to the desk, resting on the base-plate; and in this position the weight of the instrument is such as to force the base-plate into the base, or into its former retracted position 65 therein, causing the circuit to be broken at

the jack and, by means of the latch lever 14, locking the parts and positively holding the telephone in open circuit until again lifted and the push button actuated.

It is obvious, then, that in ordinary operation, the telephone circuit is manually closed and automatically opened,—the latter being automatic for the reason that no individual or separate operation is required to open the circuit when the user is in the act 70 of returning the instrument to its accustomed 75 resting place on the desk or table.

It is possible, of course, after the instrument has been lifted from the desk, to manually open the telephone circuit. It might 80 happen that the user wished to call another party before replacing the telephone on the desk. The simple act of forcing the base-plate into the base with the user's unincumbered hand locks the instrument in open circuit 85 and cuts off connection with central. Another touch on the button closes the circuit and the user is prepared to make another call.

Oftentimes a person telephoning another 90 desires to consult with a third party in his presence without the one on the other end of the line being cognizant of what is being said, or, in fact having any knowledge that the consultation is taking place at all. To 95 more clearly state the case, let us assume that A is talking with B over the telephone and that during this conversation wishes to consult C on some pertinent matter, C being in A's presence. Pushing the button 16 allows 100 A to carry on a conversation with C without B's knowledge of this fact. At the same time B may be able to talk with A although the former is absolutely cut off from anything transpiring between A and C. 105

In many instances it happens that the 110 party answering a call is not the one with whom the caller wishes to talk. In this case the one answering the call must leave the telephone to summons the proper party, but to replace the instrument on its base would 115 break connection with the central office. By means of the leg 38 the instrument may be laid on its side without interference with circuit conditions.

It is an advantage for certain reasons to 120 manually release the base-plate to bring the telephone into closed circuit, rather than to depend on simply lifting the instrument to bring this condition about. For instance, in clearing off one's desk for dusting or cleaning, or in moving the telephone from one place to another, the circuit remains open, whereas, in many types of instruments, lifting or moving the same would necessarily 125 call central for the reason that the circuit would be closed when the telephone was disturbed.

Furthermore, my invention is not to be confused with those telephones which, al- 130

though operated with one hand, require a constant pressure on a lever or button to keep the circuit closed during the entire conversational period.

- 5 In operating this latter type of instrument the user sometimes relaxes his hold on the switch button and this has the effect of notifying central exchange that the conversation is completed—with the result that 10 his line is disconnected. Nor can this class of telephone be left while the party answering leaves to summons another party wanted, without breaking connection with the central office.
- 15 The novelty of my invention as I apply it to the ordinary telephone does not in any way affect the general operation of the latter. In fact the receiver and transmitter may be of the conventional type so far as operating in connection with the elements supplied by my improvements is concerned.

But these improvements, it is believed, will add merit to the instrument now in general use and be found not only convenient but 25 vantageous in many ways.

In the foregoing I have described, and in the drawings illustrated one workable combination or embodiment of my invention which will serve to exemplify the more important features thereof; but I do not wish 30 it to be understood that I limit myself to the exact mechanical details of construction as set forth and shall deem it permissible to employ such modifications as seem desirable, 35 provided, always, that any departure from the construction as disclosed shall be conformable to the meaning and intent of the invention and co-extensive with the subjoined claims.

40 What I claim is:—

1. A telephone comprising in combination a base member, a transmitter on said base member, a handle on said base member of tubular form, a receiver fixed on said handle, a base-plate in and extending for a spaced distance below said base member, means adapted to exert a yielding pressure on the upper side of said base-plate, and means whereby said base-plate may be locked 50 against axial movement in said base when in its retracted position therein.

55 2. A telephone according to claim 1 in which there is means to manually release said base-plate from its locked position within said base member.

3. A telephone comprising in combination a base, a handle on said base, a transmitter on said base, a receiver on said handle and fixedly secured thereto, a base-plate reciprocably mounted within said base and having a portion thereof extending therebelow, means adapted to provide a yielding pressure on said base-plate tending to force it out of said base, a stud on said base-plate, guiding 60 means on said base for said stud, a head on

75 said stud, a latch-lever adapted to engage said head and lock said base-plate against axial movement thereof when in its retracted position within said base, and a push-button on said latch-lever projecting through the wall of said handle and adapted to serve as means to actuate said latch-lever whereby said base-plate may be released from its locked and retracted position within said base.

75 4. A telephone according to claim 3 having a plunger on said base-plate, a bearing on said base member adapted to receive said plunger, a conductive ferrule on but insulated from direct contact with said plunger, a 80 non-conductive sleeve on said plunger adjacent said conductive ferrule, and an insulated jack on said base member comprising a plurality of jack springs arranged around the periphery of said plunger and adapted to alternately engage the said conductive ferrule and the said non-conductive sleeve, whereby the circuit in said telephone may be, respectively, closed and opened.

85 5. A telephone comprising in combination 90 a base, a handle fixed on said base, a transmitter fixed on said base, a receiver fixed on said handle, a base-plate reciprocably mounted in said base, means to lock said base-plate in its retracted position within 95 said base, means to provide a yielding pressure on the inner side of said base-plate tending to force it out of said base, means to release said base-plate from its locked position, and a supporting leg on said handle 100 adapted to partially support said telephone and prevent its rolling when laid on its side.

105 6. A telephone comprising in combination with a base member, a handle, a receiver fixed on said handle, and a transmitter fixed on said base member, of a reciprocable base-plate in said base member, means whereby the electrical circuit through said telephone is opened when the weight of said telephone is borne by said base-plate, means whereby 110 said base-plate becomes automatically locked against axial movement in and relative to said base member when the weight of said telephone is carried by said base-plate, and means whereby said electric circuit can be 115 closed solely by means operable only after, and independently of, the lifting of said base-plate from the body supporting it.

120 7. A telephone comprising in combination a base member, a handle on said base member, a receiver fixed on said handle, a transmitter fixed on said base member, a base-plate adaptable of axial movement within said base member and depending for a 125 spaced distance below the bottom thereof, means whereby the movement of said base-plate, inwardly and outwardly of said base member, shall act to open and close, respectively, the electric circuit through said telephone, means whereby said base-plate auto- 130

matically becomes locked against axial movement in said base member when in its inward or retracted position within said base member, manually and independently operable means to release said base-plate from its locked position at any time subsequent to its being raised from its supporting body, a shutter operable to close and open the passage-way from the atmosphere into said transmitter, and means whereby said passage-way remains always closed whenever and while said base-plate is in its inwardly disposed or retracted position in said base member.

5 which said stud may reciprocate, said bushing extending upwardly into said handle, means to lock said stud against axial movement within said bushing when in its extreme inward position within said handle, a 25 shutter on said transmitter adapted to alternately open and close the passage-way to the diaphragm of said transmitter from the atmosphere, expansible means acting normally to open said shutter, and means operable to automatically close said shutter when said base-plate is forced into its retracted position in said base member.

10

15

20

8. A telephone comprising in combination a base member, a transmitter fixed on said base member, a tubular handle on said base member, a base-plate reciprocable in said base member, a stud secured in said base-plate, a guide bushing in said base member within

9. A telephone according to claim 8 and in addition, means whereby said shutter may be 35 manually closed while said base-plate is in extended position in said base member and said telephone is in a closed electrical circuit.

In testimony whereof I affix my signature.
JOHN F. PARKER.
